RAILWAY TRAFFIC CONTROLLING
APPARATUS

Charles W. Failor, Forest Hills, and John R. Henderson, Wilkinsburg, Pa., assignors to Westinghouse Air Brake Company, a corporation of Pennsylvania

Application January 15, 1948, Serial No. 2,398

10 Claims. (Cl. 246—26)

1

Our invention relates to railway traffic controlling apparatus, and particularly to apparatus embodying coded track circuits at an interlocking plant for controlling wayside signals and cab signals.

At an interlocking plant, usually most of the track sections within interlocking limits are short or include a portion of a crossover or other auxiliary track. It is therefore obviously imperative that the track circuits for these sections shall have high shunting sensitivity and shall be quick shunting. It is also important that adequate protection be provided against a momentary loss of shunt of any track circuit. Coded track circuits inherently have higher shunting sensitivity than non-coded track circuits with the same normal voltage, and provide greater protection against a momentary loss of shunt than non-coded track circuits.

Where cab signals are operated within interlocking limits, it is particularly important that the track circuits shall be quick shunting so that the cab signals shall respond quickly to any change in traffic conditions. It is also important that adequate overrun protection be provided, so that if a train should pass a stop signal for a route which conflicts with a route for which a proceed signal is being displayed or which is already occupied by another train which has been given a proceed signal indication and is therefore authorized to enter its route, the authorized train will at once be given a restricting or a proceed cab signal indication according to the location of the authorized train in its route at the time an unauthorized train passes the stop signal, and the unauthorized train will continue to receive a restricting cab signal indication.

One feature of our invention is the provision of a novel and improved arrangement for applying cab signal control energy to the relay end of a track circuit for a track section over which traffic normally moves in both directions.

Another feature of our invention is the provision of an arrangement embodying a floater track relay for giving overrun protection.

Another feature of our invention is the provision of an arrangement for controlling an approach stick cab signal relay so that it will not become energized in response to an unauthorized train passing a stop signal onto its route.

Another feature of our invention is the provision of an arrangement for controlling track circuit current for controlling the cab signal of an authorized train to display a proceed or a restricting indication according as the authorized

2

train is ahead of or is back of a point at which an approaching unauthorized train would conflict with movement of the authorized train, at the time the unauthorized train enters the conflicting route.

Still another feature of our invention is the provision of a novel and improved arrangement for resetting a coded track circuit by first energizing the track circuit by non-coded current when its track section becomes unoccupied after having been occupied by a train.

We shall describe three forms of apparatus embodying our invention, and shall then point out the novel features thereof in claims.

15 In the accompanying drawings, Figs. 1a and 1b, when placed end to end, with Fig. 1a on the left, and Figs. 1c and 1d constitute diagrammatic views showing one form of apparatus embodying our invention, in which coded track circuits are provided with interlocking limits at an interlocking plant for controlling wayside interlocking signals and for controlling cab signal control current; Fig. 2 is a diagrammatic view showing a modification of a portion of the apparatus shown in Figs. 1a and 1b for using steady alternating current for resetting a track circuit for a code change point in a cab signal control system; and Fig. 3 is a diagrammatic view showing a modification of a portion of the apparatus shown in Fig. 2 for resetting a track circuit for a code change point by coded current of a given characteristic such that it will not operate cab signals.

Similar reference characters refer to similar parts in each of the views.

In each of the views, contacts operated by the various relays or other devices are identified by numbers, such numbers having distinguishing prefixes from which they are separated by a dash 40 when the contacts are shown apart from the relay or other device by which they are operated. The prefix for each of these contact numbers comprises the reference character for the respective relay or other device by which the contact is operated. For example, contact 25TM-92, shown in the circuits for relay 21TV in Fig. 1c, is identified by the number 92 separated by a dash from the prefix 25TM which is the reference character for relay 25TM by which this contact is operated. Some contacts shown in the drawings, but which are included only in circuits which are not traced in this specification, are identified by the reference character for the relay or other device by which they are operated, followed by a dash without a number after the dash.

For example, contact 23TV-, shown in the circuit for relay 23TV in Fig. 1c, is identified by the reference character 23TV for relay 23TV by which this contact is operated followed by only a dash.

Referring first to Figs. 1a, 1b, 1c and 1d, a portion of a track layout is shown, in Figs. 1a and 1b for an interlocking plant provided with crossovers, single switches, and interlocking signals. We shall assume that the left-hand end of the track layout, as shown in Fig. 1a of the drawings, is the west end, and that, hence, the opposite or right-hand end of the track layout, as shown in Fig. 1b of the drawings, is the east end.

Traffic movements in the eastbound direction are governed by signals 4L, 24L, 26L and 26Lc. Traffic movements in the westbound direction are governed by signals 4R, 24R, 6Ra, 6Rb, and 26R. Each of the signals 4L, 4R, 24L, 24R, and 26L has an upper arm or unit a and a lower arm or unit b. Each of the signals may be of the position light type or of any other suitable design.

At the west end, an auxiliary track T is connected with a section 21T of an eastbound main track 1T by a switch 25. At the east end, a second auxiliary track ET is connected with eastbound main track 1T by a second switch 23. Two other main tracks, designated by the reference characters 2T and 3T, are interconnected by a crossover having a switch 17 at its west end and a switch E17 at its east end. Tracks 1T and 2T are interconnected by a crossover having a switch 21 at its west end and a second switch E21 at its east end, and are also interconnected by a crossover having a switch 19 at its west end and a switch E19 at its east end.

Track T is divided by insulated joints 5 to form a section 25T. Section 25T is provided with a track circuit including a suitable source of current, such as a battery 6, connected across the east end of section 25T through contacts 7 and 8 of a coding device W180CT, and a code following track relay 25TR connected across the west end of the section. Coding device W180CT is constantly energized by a suitable source having terminals B and N, and therefore this coding device repeatedly operates its contacts 7 and 8 between their front and back points at a frequency which may be 180 times per minute.

Track 1T is divided by insulated joints 5 to form sections 19T, 21T, and 23T. Each of these sections is provided with a track circuit which is supplied with coded direct current at its east end by a source such, for example, as a battery 6 connected through contacts 9 and 10 of a code repeater relay, designated by the reference character CTM preceded by the numeral for its track section, such as 21CTM for section 21T, and includes a code following track relay, such as relay 21TR which is similar to relay 25TR, connected across its west end.

A floater track relay 25XTR is connected across the rails of section 21T adjacent switch 25. A resistor 25r is connected around a pair of insulated joints 5 which is adjacent, and to the west of, switch 25, so that resistor 25r is at all times in series with the portion of the track circuit for section 21T which is west of this pair of insulated joints 5. An eastbound train on section 21T, therefore, does not deenergize relay 25XTR until the train has passed the point at which resistor 25r is connected with section 21T.

The track circuit for each of the sections 19T, 21T, and 23T also includes the secondary winding d of a cab signal transformer such, for example,

as transformer 21CF shown in Fig. 1b for section 21T, connected in series with battery 6 across the east end of the section.

Track 2T is divided by insulated joints 5 to form a section 17T. Section 17T is supplied with coded direct current at its east end similarly to sections 19T, 21T, and 23T, as just described, but the arrangement at the west end of section 17T is different from that at the west end of sections 19T, 21T, and 23T. Track relay 17TR is connected across the west end of section 17T through the back points of contacts 11 and 12 of a code following transfer relay 17WCTM. The front points of these contacts of relay 17WCTM at times close a circuit path across the west end of section 17T through secondary winding d of a cab signal transformer 17WCF.

A floater track relay 19XTR is connected across section 17T adjacent, and east of, switch 19, and a second floater track relay 21XTR is connected across section 17T adjacent, and west of, switch E21. A resistor 19r is connected with section 17T at a pair of insulated joints 5 which is adjacent, and east of, switch 19, so that resistor 19r is at all times in series with the portion of the track circuit for section 17T which is west of resistor 19r. A resistor 21r is connected with section 17T at a pair of insulated joints 5 which is adjacent, and west of, switch E21, so that resistor 21r is at all times in series with the portion of the track circuit for section 17T which is west of resistor 21r.

Track 3T is divided by insulated joints 5 to form a section 13T. Section 13T is provided with a track circuit which is similar to that for section 17T except that the battery is at the west end, and the track relay is at the east end of section 13T. Secondary windings d of cab signal transformers are connected across the ends of section 13T similarly to those for section 17T.

From the foregoing description, it follows that each of the sections 13T and 17T is provided with apparatus for supplying cab signal control energy to its west end as well as to its east end for controlling cab signals for westbound trains as well as for eastbound trains, whereas each of the sections of track 1T is provided with apparatus for supplying cab signal control energy to the east end only for controlling cab signals for eastbound trains only, and section 25T is not supplied with cab signal control energy for either direction of traffic movements. Therefore, any train moving over section 25T will never receive a proceed cab signal indication, but will always have a restrictive cab signal indication.

Energization of primary winding m of each of the cab signal transformers is effected by a circuit which includes the front point of a contact of an approach stick cab signal relay designated by the reference character TV with a numerical prefix which is the same as that for the associated track section. Each of the cab signal relays is normally deenergized, and therefore each of the cab signal transformers is normally deenergized, and its primary winding m is connected in a closed path which includes a back point of the contact of the associated cab signal relay.

For example, energization of cab signal transformer 17CF, shown in Fig. 1b, is effected by a circuit which is controlled by the front point of contact 17TV-78, but, since relay 17TV is normally deenergized, primary winding m of transformer 17CF is normally included in a closed circuit path through the back point of contact 17TV-78. Similarly, energization of primary

winding *m* of transformer 17WCF, shown in Fig. 1a, is effected by a circuit which is controlled by the front point of contact 17WTV-86, but since relay 17WTV is normally deenergized, primary winding *m* of transformer 17WCF is normally included in a closed path through the back point of contact 17WTV-86.

When relay 17WTV is energized, winding *m* of transformer 17WCF is controlled in multiple with winding *m* of an auxiliary transformer 17XF in a circuit which is controlled by a detector relay 17FSA, by a switch lever 17V for controlling operation of switches E17 and 17, and by one of the code transmitting devices which operate their contacts at a frequency of 75, 120, or 180 times per minute and are designated 15CT, 120CT, and 180CT, respectively. The code transmitters are selected by a traffic relay 2WH in accordance with traffic conditions on track 2T west of section 17T. When transformer 17XF is thus energized, relay 17WCTM is energized from the secondary winding *d* of this transformer, through a rectifier RC which comprises asymmetric units *i1*, *i2*, *i3*, and *i4*, which may be of the well-known copper oxide rectifier type.

Relay 13ECTM and transformer 13ECF for the east end of section 13T are controlled similarly to relay 17WCTM and transformer 17WCF, respectively, as just described.

The track switches shown in Figs. 1a and 1b may be operated in a well-known manner by means controlled by manually operable levers. Operation of switches 17 and E17, for example, between their normal and reverse positions, may be controlled by switch lever 17V which has a normal position *n* for controlling operation of switches 17 and E17 to their normal positions in which they are shown in the drawings, and has a reverse position *r* for controlling operation of switches 17 and E17 to their reverse positions. Lever 17V also has a normal lock position *b* and a reverse lock position *d*.

Contacts operated by each of the switch levers, as shown in Figs. 1a, 1b and 1c of the accompanying drawings, and also contacts operated by signal levers shown in Fig. 1d which will be referred to later in the specification, are shown as circles in which are placed reference characters to show the positions of the levers in which the contacts are closed. Contact 84 of lever 17V shown in the lower left-hand portion of Fig. 1a, for example, is closed when lever 17V is in its normal position *n* or in its normal lock position *b* or at any other point between these two positions.

First detector relays 13FSA, 19FSA, 21FSA, 23FSA and 25FSA are energized by circuits which are controlled by track relays 13TR, 19TR, 21TR, 23TR and 25TR, respectively, which are similar to the circuit shown in Fig. 1a for energizing relay 17FSA by the front point of contact 17TR-28. Second detector relays 13BSA, 19BSA, 21BSA, 23BSA, and 25BSA are energized by circuits which are controlled by associated track relays and first detector relays, having the same numerical prefix, which are similar to the circuit shown in Fig. 1a for energizing relay 17BSA through the back point of contact 17TR-28 and through a front contact of relay 17FSA.

First slow pick-up relays 13BSAM, 19BSAM, 21BSAM, 23BSAM, and 25BSAM are energized by circuits controlled by second detector relays, having corresponding numerical prefixes, which are similar to the circuits shown in Fig. 1a for energizing relay 17BSAM through a front contact 32 of relay 17BSA. Second slow pick-up relays 13TM, 19TM, 21TM, 23TM, and 25TM are ener-

gized by circuits controlled by the first slow pick-up relays, having corresponding numerical prefixes, which are similar to the circuit shown in Fig. 1a for energizing relay 17TM through a front contact 33 of relay 17BSAM.

Code repeater relays 13CTM, 19CTM, 21CTM, and 23CTM are energized by circuits controlled by track and detector relays, having corresponding numerical prefixes, and by code transmitter M180CT, which are similar to the circuits shown in Fig. 1a for energizing relay 17CTM by code transmitter M180CT and by detector relays 17FSA and 17BSA.

Circuits for controlling the approach stick cab signal relays are shown in Fig. 1c. These relays are controlled in part by signal control relays such, for example, as relays 24LaH and 24LJ, as shown for relay 17TV.

Signal 24L may be controlled in a well-known manner by relays 24LaH and 24LJ to display a given proceed indication when relay 24LaH is energized, and to display a given different proceed indication when relay 24LJ is energized. Relay 24LaH is controlled in part by a contact of a track indication relay 24LA in a circuit, only a portion of which is shown in the drawing.

The signal control relays may be controlled in part manually, as well as in part automatically by traffic conditions in advance of the signals which they control.

Pick-up and stick circuits for a code selecting stick relay 3U are also shown in Fig. 1c.

In Fig. 1d, pick-up and stick circuits are shown for track stick relays 13TS, 17TS and 21TS. The pick-up circuit for each of these relays includes a normal or *n* contact of a control lever for a signal which governs traffic movements over a corresponding track section.

Each of the signal control levers has a normal position *n* and two reverse positions *f* and *r* for controlling eastbound or westbound signals respectively.

Also in Fig. 1d, control circuits are shown for track indication relays 4LA, 24LA and 28LA.

Control circuits for floater repeater relay 21XTM and floater stick relays 25XTM and 25S, and for floater detector relays 19XFSA and 19XBSA are also shown in Fig. 1d.

Referring next to Fig. 2, a stretch of track Y of an electric railway is shown, on which the propulsion current for train operation may have a frequency of 25 cycles per second. Track Y is shown divided by insulated joints 5 to form a block *a-c*. Impedance bonds 27 of a well-known type are provided at the ends *a* and *c* of this block.

A signal 1S governs traffic movements into block *a-c*, and a second signal 2S governs traffic movements from block *a-c* into the next block 60 east of block *a-c*. Signal 2S is an interlocking signal, and is therefore shown normally at stop. Signals 1S and 2S may be of the position light type or of any other suitable design.

A portion of an operating circuit for signal 2S 65 is shown controlled by a contact of a signal relay 2H. Relay 2H is in turn controlled by a circuit, a portion of which is shown, including a contact of a track relay 2TR for track Y in advance of signal 2S.

Current for energizing a track relay 1TR and for controlling cab signals is supplied to block *a-c* by a track transformer 1F. A code following floater track relay, designated by the reference character XTR, is connected through a resonant transformer rectifier unit RT across the

7 rails of block *a*—*c* at a point *b* which is known as a code change point for cab signals. Relay XTR is therefore also energized from transformer IF through the rails of portion *b*—*c* of block *a*—*c*.

A detector relay FSA is controlled by a circuit which includes the front point of a contact of relay XTR. A second detector relay BSA is controlled by relays XTR and FSA.

Primary winding *m* of transformer IF is at times energized through a back point of contact 114 of relay 2H, and through contacts of relays FSA and BSA and a code transmitter 15CT. Primary winding *m* of transformer IF is also at times energized through the front point of contact 114 of relay 2H by a circuit controlled by relay 2TR and a code transmitter 180CT.

Referring now to Fig. 3, a special coding device XCT is here provided for coding the current at a frequency to which the cab signaling apparatus will not respond. The coded current thus produced may be of a low frequency such, for example, as 20 cycles per minute, or it may be of a limp code such as short on and long off. Detector relays XFSA and XBSA are controlled similarly to the manner in which relays FSA and BSA are shown controlled in Fig. 2. The purpose of relays XFSA and XBSA in Fig. 3 is to serve as checking means for the operation of device XCT, so that if contact 120 of device XCT should become constantly closed, the circuit for primary winding *m* of transformer IF will be opened at contact 121 of relay XBSA. Current coded by device XCT is supplied to the primary winding *m* of transformer IF when relays BSA and 2H, shown in Fig. 2, are deenergized.

Having described, in general, the arrangement and control of the apparatus shown by the accompanying drawings, we shall now describe, in detail, its operation.

As shown by the drawings, all parts are in their normal condition, that is, the track sections are unoccupied and therefore all track relays are energized by coded current; each of the signals shown in Figs. 1a and 1b and signal 2S shown in Fig. 2 are indicating stop; signal 1S shown in Fig. 2 is indicating caution; each of the switch and signal levers is in its *n* position; each of the coding devices CT is constantly energized, and is therefore repeatedly moving its contacts between the front and back points; each of the cab signal transformers CF, and each of the auxiliary transformers XF is deenergized; each of the traffic relays EH and WH is energized by current of normal polarity; each of the detector relays FSA and BSA; each of the slow pick-up relays BSAM and TM, each of the code repeater relays CTM, relay 3U, each of the track stick relays TS, each of the track indication relays LA, each of the floater stick and repeater relays XTM, and relay 25s are energized; and relays 13ECTM and 17WCTM, each of the cab signal relays TV, and relay 2H, shown in Fig. 2, are deenergized.

In Fig. 1a, the circuit by which relay 25TR is periodically energized passes from the positive terminal of a battery 6, through the back points of contacts 7 and 8 of coding device E180CT in multiple, upper rail of section 25T, as shown in the drawing, winding of relay 25TR, and lower rail of section 25T, back to the negative terminal of battery 6. In order to diminish the road bed storage battery effect, the rails of section 25T are periodically shunted by the front points of contacts 7 and 8 of coding device W180CT.

The circuit by which relay 21TR is energized

passes from the positive terminal of a battery 6, through the back points of contacts 21CTM-9 and 21CTM-10 in multiple shown in Fig. 1b, upper rail of section 21T, as shown in the drawing, to switch 25, thence by the lower rail to the winding of relay 21TR, upper rail of section 21T, through resistor 25r to the lower rail, and secondary winding *d* of transformer 21CF back to battery 6. Floater track relay 25XTR is energized by a circuit which is similar to the one just traced for relay 21TR except that it does not include resistor 25r and does not include the rails between resistor 25r and signal 26L. Relays 19TR and 23TR are also energized by circuits which are similar to the circuit traced for relay 21TR except that they do not include a resistor such as resistor 25r.

The circuit by which relay 17TR is energized passes from the positive terminal of a battery 6, 20 through the back points of contacts 17CTM-9 and 17CTM-10 in multiple, to the upper rail of section 17T, as shown in the drawing, resistor 19r to the lower rail, resistor 21r to the upper rail, winding of relay 17TR, through the back points of contacts 11 and 12 of relay 17WCTM in multiple with each other, lower rail of section 17T to switch E21, thence by the upper rail to switch 19, thence to the lower rail, and through secondary winding *d* of transformer 17CF back to the negative side of battery 6. Relay 19XTR is energized by a circuit which is the same as the circuit just traced for relay 17TR to the point at which relay 19XTR is connected across the rails of section 17T. Relay 21XTR is energized by a circuit which is similar to the circuit traced for relay 17TR except that it does not include resistor 21r and does not include the portion of section 17T which is west of resistor 21r.

40 The circuit by which relay 13TR is energized is similar to the circuit traced for relay 17TR except that it does not include any resistors.

The circuit by which relay 17FSA is energized, as shown in Fig. 1a, passes from terminal B, 45 through the front point of contact 17TR-28, and the winding of relay 17FSA in multiple with a resistor 29 and the high resistance direction of an asymmetric unit 30 to terminal N. The circuit by which relay 17BSA is energized passes from terminal B, through the back point of contact 17TR-28, and contact 34 of relay 17FSA and the winding of relay 17BSA, in multiple with a resistor 29 and the high resistance direction of an asymmetric unit 30 to terminal N. Relay 55 17BSAM is energized by an obvious circuit controlled by contact 32 of relay 17BSA. Relay 17TM is energized by an obvious circuit controlled by contact 33 of relay 17BSAM. Relay 17CTM is periodically energized by a circuit passing from terminal B, through contact 34 of coding device M180CT, front point of contact 36 of relay 17BSA, and the winding of relay 17CTM in multiple with resistor 29 and the high resistance direction of an asymmetric unit 30 to terminal N.

60 Relay 3U, shown in Fig. 1c, is energized by a circuit passing from terminal B, through contacts 19V-37 and 21V-38, contact 39 of lever 23V, back point of contact 19TV-41, back point of contact 23TV-42, and the winding of relay 3U to terminal N.

Both a pick-up and a stick circuit are closed for energizing each of the track stick relays 13TS, 17TS, and 21TS, shown in Fig. 1d. The pick-up circuit for relay 13TS, for example, passes

from terminal B, through contact 13TM-43, contact 46 of lever 4V, and the winding of relay 13TS to terminal N. The stick circuit for this relay passes from terminal B, through contact 13TM-43, contact 13TS-45, and the winding of relay 13TS to terminal N. The pick-up and stick circuits for relays 17TS and 21TS are similar to those just traced for relay 13TS, and can therefore be readily traced on the drawing.

Track indication relay 4LA, shown in Fig. 1d, is energized by an obvious circuit controlled by contact 13TS-47. Relay 24LA is energized by a circuit passing from terminal B, through contact 17TS-47, contact 26LA-48 in multiple with contact 19V-49, contact 4LA-50 in multiple with contact 17V-51, and the winding of relay 24LA to terminal N. Relay 26LA is energized by a circuit passing from terminal B, through contact 21TS-47, contacts 19TM-52, 23TM-53, and 21V-59, and the winding of relay 26LA to terminal N.

Both a pick-up and a stick circuit are closed for energizing relay 25S, shown in Fig. 1d. The pick-up circuit for this relay passes from terminal B, through contacts 25XTM-60 and 25TM-61, and the winding of relay 25S to terminal N. The stick circuit for relay 25S is the same as the pick-up circuit just traced except that it includes contact 25S-62 instead of contact 25TM-61.

We shall assume that, with apparatus as shown in Figs. 1a, 1b, 1c and 1d, the upper arm *a* of signal 24L is controlled, by energization of relay 24LaH, to display a proceed indication. An eastbound train, upon passing signal 24L, deenergizes relay 17TR, thereby causing relays 17FSA, 17BSA, 17BSAM, 17CTM, and 17TM to be deenergized in the order named.

With relay 24LaH energized to control signal 24L to display a proceed indication at the time the eastbound train enters section 17T, cab signal relay 17TV becomes energized by a circuit passing from terminal B, through contact 17TM-64, contact 65 of relay 24LaH, and the winding of relay 17TV to terminal N. Relay 17TV, upon becoming energized, closes its own stick circuit which is the same as the pick-up circuit just traced except that it includes contact 17TV-67 instead of contact 65 of relay 24LaH.

Deenergization of relay 17TM causes contact 17TM-43 to open the circuits described for relay 17TS, so that relay 17TS becomes deenergized. Relay 17TS, upon becoming deenergized, opens at its contact 17TS-47, the circuits previously traced for relay 24LA. Relay 24LA then opens its contact 24LA-63, causing relay 24LaH to become deenergized. Relay 17TV, however, remains energized by its stick circuit previously traced. With relay 17TV energized, cab signal transformer 17CF becomes energized by a circuit passing from terminal BX of a suitable source of alternating current, through contact 72 of coding device E180CT, contact 73 of relay 2EH closed in the normal or left-hand position, contact 74 of relay 2EH, contacts 21V-75 and 17V-76, contact 77 of lever 19V, front point of contact 17TV-78, and primary winding *m* of transformer 17CF to terminal NX of the same source of alternating current. With transformer 17CF energized, cab signal control current is supplied to section 17T in the circuit previously traced for energizing relay 17TR. This cab signal control current is coded at a rate, for example, of 180 times per minute, to control the cab

signal on the train to display a proceed indication.

If relay 2EH should now become deenergized, its contact 74 would open the circuit traced for 5 transformer 17CF, thereby discontinuing the cab signal control current, and so causing the cab signal on the train to display a restrictive indication. If, on the other hand, relay 2EH should now become energized by current of reverse 10 polarity, primary winding *m* of transformer 17CF would become energized by current coded at a frequency of 75 times per minute, passing from terminal BX, through contact 79 of coding device E15CT, contact 73 of relay 2EH closed in the reverse position, and thence by the remainder of the path previously traced for energizing winding *m* of transformer 17CF by current coded 180 times per minute. With cab signal control current coded at a rate of 75 times per minute being supplied to track section 17T, the cab signal on the train would display a corresponding proceed indication.

Relay 21XTR remains energized until the train passes insulated joints 5 at resistor 21r and relay 25 19XTR remains energized until the train passes insulated joints 5 at resistor 19r.

When the train leaves section 17T, steady direct current is first supplied to section 17T by the circuit, previously traced, including contacts

30 17CTM-9 and 17CTM-10 which are now constantly closed at their back points because relay 17CTM is now deenergized. With relay 17TF thus energized by steady direct current, relay 17FSA becomes constantly energized by its circuit previously traced. With relay 17FSA now energized, relay 17CTM becomes energized by steady current passing from terminal B, through contact 35 of relay 17FSA, back point of contact 36 of relay 17BSA, and the winding of relay 40 17CTM in multiple with resistor 29 and asymmetric unit 30 to terminal N. Relay 17CTM, upon becoming energized, opens the circuit previously traced for relay 17TR through contacts 17CTM-9 and 17CTM-10, causing relay 17TR to become deenergized. With relay 17TR deenergized, relay 17BSA becomes energized by its circuit previously described. With relay 17BSA energized, the circuit previously traced for relay 17CTM through contact 34 of coding device 50 M180CT is now again closed, causing relay 17CTM to be again periodically energized and to thereby restore the track circuit for section 17T to its normally coded operation.

When relay 17TM now becomes energized, relay 55 17TV becomes deenergized, causing transformer 17CF to also be deenergized and to therefore discontinue the supply of cab signal control current to section 17T.

We shall now assume that all parts of the apparatus are again in the normal condition, and that signal 24R is controlled by energization of 60 relay 24RaH to display a proceed indication for a westbound train. When the westbound train passes signal 24R, relays 17TR, 19XTR, and 21XTR become deenergized.

With relay 24RaH energized for controlling signal 24R to display a proceed indication at the time the westbound train enters section 17T, relay 17WTV becomes energized by a pick-up circuit passing from terminal B, through contact 17TM-80, contact 65 of relay 24RaH, and the winding of relay 17WTV to terminal N. Relay 17WTV, upon becoming energized, closes its own stick circuit which is the same as the pick-up 70 circuit just traced except that it includes con-

11

tact 17WTV-67 instead of contact 65 of relay 24RaH.

Relay 17FSA, upon becoming deenergized, completes a circuit for energizing auxiliary transformer 17XF, shown at the left-hand end of Fig. 1a, this circuit passing from terminal BX, through contact 81 of coding device 180CT, contact 82 of relay 2WH closed in the normal position, contact 83 of relay 2WH, contact 84 of lever 17V, contact 17FSA-85, and primary winding *m* of transformer 17XF, to terminal NX.

When relay 17WTV becomes energized, primary winding *m* of transformer 17WCF also becomes energized by a circuit which is the same as the circuit just traced for transformer 17XF as far as contact 17FSA-85, and which then passes through the front point of contact 17WTV-86, and primary winding *m* of transformer 17WCF to terminal NX. With primary winding *m* of transformer 17WCF now energized by current passing through contact 81 of coding device 180CT, cab signal control current coded at a frequency of 180 times per minute is supplied to the rails of section 17T from secondary winding *d* of transformer 17WCF, through the front points of contacts 11 and 12 of relay 17WCTM during their closed periods. The cab signal of the westbound train on section 17T therefore displays a corresponding proceed indication.

When the westbound train enters the first section of track 2T west of section 17T, relay 2WH becomes deenergized, and therefore its contact 83 opens the circuits previously traced for energizing transformers 17WCF and 17XF, so that relay 17WCTM becomes deenergized.

When the westbound train leaves section 17T, relay 17TR again becomes energized by steady direct current as previously described for an eastbound train leaving section 17T. With relay 17TR energized, relay 17FSA becomes energized, as previously described, causing relay 17CTM in turn to become energized by steady direct current passing through the back point of contact 36 of relay 17BSA. Relay 17CTM then opens the circuit for relay 17TR, causing relay 17TR to become deenergized. Relay 17BSA then becomes energized as previously described, and relay 17CTM in turn becomes energized by its circuit through contact 34 of coding device M180CT. With relay 17TR now energized by coded current of 180 cycles per minute controlled by the back points of contacts 17CTM-9 and 17CTM-10, the apparatus is restored to its normal condition.

Relay 17TM, upon becoming energized, opens the circuit previously traced for relay 17WTV through contact 17TM-80, thereby causing relay 17WTV to be deenergized. With transformer 17WCF thus deenergized, the westbound cab signal control current previously supplied to section 17T is discontinued.

The winding of relay 19XFSA and the branch path including resistor 29 and asymmetric unit 30 in multiple with this winding are proportioned so that if an unauthorized westbound train should enter section 17T while switches 17 and E17 are in the reverse position, the front contacts of relay 19XFSA will open before the back contacts of relay 17TM become closed.

We shall next assume that section 17T becomes occupied by an eastbound light engine, and that a momentary loss of shunt of the track circuit occurs. Relay 17TR, therefore, first becomes energized by steady direct current, as previous-

12

ly described, causing relay 17FSA to also become energized. Relay 17CTM is then energized, as previously described, causing relay 17TR to again become deenergized, with the result that relay 17BSA becomes energized. With relay 17BSA energized, the circuit for energizing relay 17BSAM is closed, but this relay is slow picking up, so its contact 33 does not become closed until after the lapse of a brief period of time. If the loss of shunt period lasts long enough, the circuit for relay 17TM will be closed through contact 33 of relay 17BSAM. However, it is unlikely that a momentary loss of shunt will last long enough for relay 17TM, which is also of the slow pick-up type, to close its front contacts. The circuits controlled by relay 17TM will therefore not be affected by a momentary loss of shunt.

We shall now assume that all parts of the apparatus are again in the normal condition, and that lever 26V is moved to its *f* position for controlling unit *a* of signal 26L to display a proceed indication for an eastbound train, and that signal 26Lc is displaying a stop indication. We shall assume further that, while an eastbound train is approaching signal 26L, a second train overruns signal 26Lc, that is, it stops with its front wheels on section 25T, so that relay 25TR becomes deenergized, causing relay 25TM in turn to also be deenergized. We shall refer to the first train, which is given a proceed indication by signal 26L, as an authorized train, and we shall refer to the second train which is given a stop indication by signal 26Lc, as the unauthorized train.

With section 21T not yet occupied by the authorized train, relay 25XTR, as well as relay 21TR, will still be energized. With lever 26V in its *f* position while relay 25XTR is energized, relay 25XTM becomes energized by a pick-up circuit passing from terminal B, through contact 25XTR-87, resistor 29 and asymmetric unit 30 in multiple with the winding of relay 25XTM, and contact 26V-88 to terminal N. Relay 25XTM, upon becoming energized, closes its stick circuit, which is the same as the pick-up circuit just traced except that it includes contact 25XTM-89 instead of contact 26V-88. With relay 25XTM energized, contact 25XTM-60 becomes opened, causing relay 25S to be deenergized.

If, now, with relay 25S thus deenergized, and with relay 25TM deenergized by the unauthorized train, the authorized train passes signal 26L, cab signal relay 21TV cannot become energized when back contact 21TM-64 becomes closed, because contacts 25TM-92 and 25S-93 in the circuit for relay 21TV are now open. Cab signal transformer 21CF, therefore, remains deenergized, so that no cab signal control current is supplied to section 21T. The authorized train will, therefore, not receive a proceed cab signal indication, but will receive a restrictive cab signal indication.

We shall next assume that, instead of the unauthorized train overrunning signal 26Lc before the authorized train passes signal 26L, the authorized train passes signal 26L before the unauthorized train enters section 25T.

When the authorized train now enters section 21T, relay 21TV becomes energized by a circuit passing from terminal B, through contact 21TM-64, contact 65 of relay 26LaH, contact 25TM-92 in multiple with contact 25S-93, and the winding of relay 21TV to terminal N. Relay 21TV, upon becoming energized, completes its own stick circuit, which is the same as the

pick up circuit just traced except that it includes contact 21TV-67 instead of contact 65 of relay 26LaH

With relay 21TV energized, cab signal transformer 21CF becomes energized by current passing from terminal BX, through contact 94 of coding device E120CT, front point of contact 3U-95, contact 96 of relay 1EH closed in the normal position, contact 97 of relay 1EH, contacts 23TM-98 and 19TM-99, contact 100 of lever 21TV, front point of contact 21TV-101, and primary winding *m* of transformer 21CF to terminal NX. With transformer 21CF thus energized by current coded at a frequency of 180 times per minute, cab signal control current of this frequency is supplied to the rails of section 21T for controlling the cab signal of the authorized train to display a corresponding proceed cab signal indication.

If, now, the unauthorized train passes signal 26Lc deenergizing relay 25TM before the authorized train passes insulated joints 5 at resistor 25r and, therefore, while relay 25XTR is still energized, relay 25XTM is energized, and hence relay 25S is deenergized, and, therefore, relay 21TV becomes deenergized due to relays 25S and 25TM being deenergized. With relay 21TV thus deenergized, the cab signal current being supplied to section 21T is discontinued, and the proceed cab signal indication is taken away from the authorized train.

If, however, the authorized train has proceeded far enough to deenergize relay 25XTR before the unauthorized train deenergizes relay 25TM, relay 25S will become energized by its pick-up circuit, and will then remain energized by its stick circuit after the unauthorized train deenergizes relay 25TM. Contact 25S-93 will therefore remain closed in the stick circuit for relay 21TV, so that cab signal control current will continue to be supplied to section 21T, and the authorized train will continue to receive a proceed cab signal indication.

We shall next assume that all parts of the apparatus are again in the normal condition and that switch lever 21V is moved to its *r* position for effecting operation of switches 21 and E21 to their reverse position, and that lever 26V is moved to its *f* position, so that relays 26LbH and 26LJ are energized for controlling unit *b* of signal 26L to display a proceed indication while signal 24L is controlled to indicate stop.

If, now, an unauthorized train passes signal 24L before an authorized train passes signal 26L, relays 17TR and, in turn, 17TM will be deenergized. With relay 21XTR still energized, and with lever 21V in its *r* position, relay 21XTM will be energized by a circuit passing from terminal B, through contact 21XTR-102, winding of relay 21XTM in multiple with a resistor 29 and an asymmetric unit 30, and contact 21V-103 to terminal N. With signal 24L controlled to indicate stop, relays 24LaH and 24LJ are both deenergized.

Since relay 21XTM is now energized, its contact 21XTM-69 is open in one of the pick-up circuits for relay 17TV. Contact 21TV-70 is also open in the same pick-up circuit for relay 17TV. Relay 17TV therefore does not become energized when the unauthorized train passes signal 24L. The unauthorized train, therefore, receives a restricting cab signal indication.

When relay 17TM becomes deenergized, its contact 17TM-43 opens in the circuits for relay 17TS, and hence relay 17TS becomes deenergized. With

relay 17TS deenergized, its contact 17TS-41 is open in the circuits for relay 24LA, causing relay 24LA to also be deenergized.

- If the authorized train passes signal 26L before the unauthorized train passes signal 24L, relay 21TV becomes energized by a circuit passing from terminal B, through contact 21TM-64, contact 90 of relay 26LbH, contact 91 of relay 26LJ, contact 25TM-92 in multiple with contact 10 25S-93, and the winding of relay 21TV to terminal N. Cab signal transformer 21CF is therefore now energized by current passing from terminal BX, through contact 104 of coding device E120CT, contacts 105 and contact 106 of relay 2EH, contacts 17TM-107, 23TM-108, and 19TM-109, contact 110 of lever 21V, front point of contact 21TV-101, and primary winding *m* of transformer 21CF to terminal NX. With current coded at a frequency of 120 times per minute thus supplied to transformer 21CF, cab signal current correspondingly coded is supplied to the rails of section 21T for controlling the cab signal on the authorized train to display a corresponding proceed indication.
- 25 If, now, an unauthorized train passes signal 24L while the authorized train is on section 21T, contact 17TM-107 will open the circuit last previously traced for cab signal transformer 21CF, thereby removing cab signal control current from section 21T and causing the authorized train to receive a restricting cab signal indication.

- If, however, the authorized train deenergizes relay 21XTR before the unauthorized train passes signal 24L, relay 21XTM will become deenergized, 35 thereby completing a circuit for relay 17TV passing from terminal B, through contacts 17TM-64, 24LA-68, 21XTM-69, 21TV-70, and 21V-71, and the winding of relay 17TV to terminal N. With relay 17TV energized, current coded at a frequency of 120 times per minute will be supplied to cab signal transformer 17CF by a circuit passing from terminal BX, through contact 104 of coding device E120CT, contacts 105 and 106 of relay 2EH, contacts 21V-111 and 17V-76, contact 77 of lever 40 19V, front point of contact 17V-78, and winding *m* of transformer 17CF to terminal NX. With cab signal current coded at a frequency of 120 times per minute thus supplied to section 17T, the authorized train will receive a corresponding proceed cab signal indication.

- If, then, the unauthorized train enters section 17T, relay 17TV will remain energized by its stick circuit, so the authorized train will continue to receive a proceed cab signal indication, and will 55 shunt the track ahead of the unauthorized train, so that the unauthorized train will receive a restrictive cab signal indication.

- In Fig. 2, track transformer 1F is shown energized by current coded at a frequency of 75 times per minute in a circuit passing from terminal BX, through contact 112 of coding devices 75CT, from point of contact 113 of relay BSA, back point of contact 114 of relay 2H, and primary winding *m* 60 of transformer 1F to terminal NX. Current coded at a frequency of 75 times per minute is therefore supplied by transformer 1F to block *a*-*c*. Code following relay XTR is therefore energized and is repeatedly closing its contact 28 alternately at its front and back points. Relay FSA is therefore energized by a circuit which includes the front point of contact 28 of relay XTR, and relay BSA is energized by a circuit passing from terminal B, through the back point of contact 28 of relay 75 XTR, contact 31 of relay FSA, and the winding

of relay BSA in multiple with resistor 29 to terminal N.

With the apparatus arranged as shown in Fig. 2, with signal 2S controlled to indicate stop, we shall assume that a train moves from left to right, as shown in the drawing, which we shall also assume is the eastbound direction. When the train arrives at the code change point b, relay XTR becomes deenergized, causing relays FSA and BSA in turn to become deenergized. Cab signal control current, coded at a frequency of 75 times per minute, is therefore discontinued, so that the train, upon passing point b, receives a restricting cab signal indication.

When the train leaves block a—c, transformer 1F first becomes energized by steady alternating current passing from terminal BX, through contact 115 of relay FSA, back point of contact 113 of relay BSA, back point of contact 114 of relay 2H, and winding m of transformer 1F to terminal NX. Relay XTR, therefore, becomes steadily energized, causing relay FSA to become energized by its circuit previously described. Relay FSA, upon becoming energized, opens its contact 115, thereby deenergizing transformer 1F and causing relay XTR to become deenergized. Relay BSA then becomes energized by its pick-up circuit previously traced, causing the circuit previously traced for transformer 1F through contact 112 of coding device 75CT to again be closed. The operation of the apparatus at points b and c is therefore restored to the normal condition.

If relay 2H is controlled to be energized for clearing signal 2S, transformer 1F is energized by current passing from terminal BX, through contact 117 of code transmitter 180CT, contact 118 of relay 2TR, front point of contact 114 of relay 2H, and winding m of transformer 1F to terminal NX. Current coded at a frequency of 180 times per minute is therefore now supplied to block a—c for controlling the cab signal of a train in the block a—c to display a corresponding proceed indication. The train, upon moving through block a—c, will now have no change in cab signal indication when it passes point b and deenergizes relays FSA and BSA.

If the apparatus of Fig. 2 is modified as shown in Fig. 3, and if an eastbound train then passes point b, deenergizing relay BSA, primary winding m of transformer 1F will be energized by current coded at a frequency to which cab signals will not respond, passing from terminal BX, through contact 120 of coding device XCT, contact 121 of relay XBSA, back point of contact 113 of relay BSA, back point of contact 114 of relay 2H, and winding m of transformer 1F to terminal NX. When block a—c now becomes vacated, relay XTR will become energized by the coded current of a frequency to which cab signals will not respond, causing relays FSA and BSA to become energized and thereby again complete the circuit for transformer 1F including contact 112 of coding device 75CT.

Although we have described the operation of the apparatus shown in the accompanying drawings for only a few typical traffic movements, it is believed that, in view of these descriptions, the operation of the apparatus for any other possible traffic movement can be traced readily by reference to the drawings, without further description.

Although we have herein shown and described only a few forms of railway traffic controlling apparatus embodying our invention, it is understood that various changes and modifications may be

made therein within the scope of the appended claims without departing from the spirit and scope of the appended claims without departing from the spirit and scope of our invention.

Having thus described our invention, what we claim is:

1. In railway traffic controlling apparatus embodying a coded track circuit for a track section within interlocking limits at an interlocking plant, in which said section is provided with a track circuit including a source of direct current connected across one end of the section and a code following track relay connected across the opposite end of the section for controlling wayside signals, in which a source of alternating current for controlling cab signals is connected across the same end of said section as said direct current source, the combination comprising, a first detector relay controlled by a front contact of said track relay, a second detector relay controlled by a back contact of said track relay in series with a front contact of said first detector relay, a slow pick-up relay controlled by a front contact of said second detector relay, a code repeater relay having a first energizing circuit controlled by a coding contact in series with a front contact of said second detector relay and having a second energizing circuit controlled by a front contact of said first detector relay in series with a back contact of said second detector relay, a back contact of said code repeater relay connected in series with said direct current source and with said alternating current source across the rails of its section, and means controlled by a back contact of said first detector relay and by a back contact of said slow pick-up relay for supplying alternating current to the relay end of its section for controlling cab signals.
2. In railway traffic controlling apparatus embodying a coded track circuit for a track section within interlocking limits at an interlocking plant, in which said section is provided with a track circuit including a source of direct current connected across one end of the section and a code following track relay connected across the opposite end of the section for controlling wayside signals, in which a source of alternating current controlled by an approach stick cab signal relay is connected across the same end of said section as said direct current source for controlling cab signals, the combination comprising, a first detector relay controlled by a front contact of said track relay, a second detector relay controlled by a back contact of said track relay in series with a front contact of said first detector relay, a slow pick-up relay controlled by a front contact of said second detector relay, a code repeater relay having a first energizing circuit controlled by a coding contact in series with a front contact of said second detector relay and having a second energizing circuit controlled by a front contact of said first detector relay in series with a back contact of said second detector relay, a back contact of said code repeater relay connected in series with said direct current source and with said alternating current source across the rails of its section, means controlled by a back contact of said first detector relay and by a back contact of said slow pick-up relay and by control means for a wayside signal for said section and also by other traffic responsive means for controlling said cab signal relay to become energized and to remain energized only if no train occupies a route including said section in advance of a point at which said train would conflict with a given train controlled by said wayside signal for

said section before said given train passes said point, and means controlled by a front contact of said cab signal relay for controlling said source of alternating current for supplying alternating current to said section for controlling cab signals.

3. In railway traffic controlling apparatus for a track section at an interlocking plant, in which said section is provided with a track circuit including a source of direct current connected across one end of the section and a code following track relay connected across the opposite end of the section for controlling a wayside signal, in which a source of alternating current for controlling cab signals is connected across the same end of the section as said direct current source, the combination comprising, a detector relay controlled by a front contact of said track relay, a second detector relay controlled by a back contact of said track relay in series with a front contact of said first detector relay, a code repeater relay having an energizing circuit controlled by a coding contact in series with a front contact of said second detector relay and having a second energizing circuit controlled by a front contact of said first detector relay in series with a back contact of said second detector relay, a back contact of said code repeater relay connected in series with said direct current source and with said alternating current source across said one end of said section, an approach stick cab signal relay having a pick-up and a stick circuit each of which is controlled by a contact which is closed if said second detector relay is deenergized and said pick-up circuit also controlled by a contact which is closed if a wayside signal for said one end of said section is controlled to display a proceed indication, a cab signal transformer, an auxiliary transformer, means controlled by a back contact of said first detector relay and by a front contact of said cab signal relay for energizing the primary winding of said cab signal transformer, means controlled by a back contact of said first detector relay for energizing said auxiliary transformer by coded current, a code following transfer relay energized from the secondary winding of said auxiliary transformer, a back contact of said transfer relay connected in series with the winding of said track relay across said section, and a front contact of said transfer relay connected in series with the secondary winding of said cab signal transformer across said section adjacent said track relay for controlling cab signals.

4. In railway traffic controlling apparatus for a track section at an interlocking plant, in which said section is provided with a track circuit including a source of direct current connected across one end of the section and a code following track relay connected across the opposite end of the section for controlling a wayside signal, in which a source of alternating current for controlling cab signals is connected across the same end of the section as said direct current source, the combination comprising, a detector relay controlled by a front contact of said track relay, a second detector relay controlled by a back contact of said track relay in series with a front contact of said first detector relay, a code repeater relay having an energizing circuit controlled by a coding contact in series with a front contact of said second detector relay and having a second energizing circuit controlled by a front contact of said first detector relay in series with a back contact of said second detector relay, and a back

contact of said code repeater relay connected in series with said direct current source and with said alternating current source across said one end of said section.

5. In traffic controlling apparatus for a section of railway track embodying a track circuit for said section which includes a code following track relay connected across said section, the combination comprising, a detector relay controlled by a front contact of said track relay, a second detector relay controlled by a back contact of said track relay in series with a front contact of said first detector relay, and means controlled by said first and second detector relays for supplying current of a given character to said section when said section becomes vacated after being occupied by a train and controlled by a front contact of said second detector relay for periodically supplying current of said given character to said section.
6. In track circuit apparatus for controlling traffic governing means for a section of railway track, including a code following track relay connected across said section, the combination comprising, a detector relay controlled by a front contact of said track relay, a second detector relay controlled by a back contact of said track relay in series with a front contact of said first detector relay, means for supplying current of a given character to said section for energizing said track relay when said section becomes vacated after being occupied by a train, and means controlled by a front contact of said second detector relay for supplying coded current to said section.
7. In railway traffic controlling apparatus for a track section at an interlocking plant, in which said section is provided with a track circuit including a source of coded direct current connected across one end of the section and a code following track relay connected across the opposite end of the section for controlling a wayside signal, in which a source of alternating current controlled in part by said code following track relay for controlling cab signals is connected across the same end of the section as said source of coded direct current, the combination comprising, an approach stick cab signal relay controlled to become energized if a train enters said one end of said section while a signal is indicating proceed for said train to enter said section and to remain energized while said train occupies said section, and means controlled by a front contact of said cab signal relay while said track relay is deenergized by a train in said section for supplying alternating current to the track relay end of said section for controlling cab signals.
8. In a railway traffic control system for two routes which converge at a switch in an interlocking plant, in which two wayside signals are provided one for each of said routes for governing trains entering the corresponding routes, the combination comprising, a track section embodied in one of said routes including said track switch, a second track section for the other route extending between said wayside signal for its route and said switch but not including said switch, a track circuit for said first section including a track relay connected across the rails adjacent its signal for controlling its signal and including a source of current connected across the opposite end, means controlled by a train upon entering the relay end of said first track section for supplying proceed cab signal control current to said opposite end, a floater track relay

connected across the rails of said track circuit adjacent said switch and arranged to remain energized until a train on either route arrives at a point adjacent said switch, and means controlled by said floater track relay for retaining proceed cab signal control current for a train on said first route which has entered said first route in response to a proceed indication of its wayside signal only if said train arrives at a point adjacent said switch before a second train enters said second route.

9. In a railway traffic control system for two routes which converge at a switch in an interlocking plant, in which two wayside signals are provided one for each of said routes for governing trains entering the corresponding routes, the combination comprising, a track section embodied in one of said routes including said track switch, a second track section for the other route extending between said wayside signal for its route and said switch but not including said switch, a track circuit for said first section including a track relay connected across the rails adjacent its signal for controlling its signal and including a source of current connected across the opposite end, a floater track relay connected across the rails of said track circuit adjacent said switch and arranged to remain energized until a train on either route arrives at a point adjacent said switch, a floater stick relay controlled to become energized if the signal for said first route is controlled to display a proceed indication while said floater track relay is energized, a second floater stick relay controlled to become energized if said first floater stick relay is deenergized while said second track section is unoccupied, a cab signal relay controlled to become energized only if said second track section is unoccupied or if said second floater stick relay is energized, and means controlled by a front contact of said cab signal relay for supplying cab signal control current to said first track section.

10. In railway traffic controlling apparatus embodying track circuits for a plurality of track sections within interlocking limits at an interlocking plant, in which each section is provided with a track circuit including a source of direct current connected across one end of the section and a track relay connected across the opposite end of the section for controlling a wayside signal, the combination comprising, a first route including a first track section, a signal for governing traffic movements onto said first route, a second route including a second section between its entrance end and a point at which it converges into said first route, a first stick relay controlled to become energized when said signal is cleared and to then remain energized until a train on either said first or said second route arrives adjacent said point at which said routes converge, a second stick relay controlled to become energized only if said first stick relay is deenergized and if said second section is unoccupied and to then remain energized as long as said first stick relay is deenergized, a cab signal relay controlled to become energized if said first section becomes occupied while said signal is controlled to display a proceed indication and if said second section is unoccupied or said second stick relay is energized, and means controlled by said cab signal relay upon becoming energized for supplying cab signal control current to said first section.

CHARLES W. FAILOR.
